United States Patent Office.

GARRETTSON SMITH AND HENRY BROWN, OF PHILADELPHIA, PENNSYLVANIA, ASSIGNORS TO BUCKWALTER & CO.

Design No. 2,587, dated February 26, 1867.

DESIGN FOR THE PLATES OF A COOK'S STOVE.

The Schedule referred to in these Letters Patent and making part of the same.

TO ALL WHOM IT MAY CONCERN:

Be it known that we, GARRETTSON SMITH and HENRY BROWN, of Philadelphia, county of Philadelphia, State of Pennsylvania, have invented or produced a new and original Design for Plates of a Cooking Stove, termed the Eclipse; and we do hereby declare that the accompanying drawing, and the following explanation thereof, form a full, clear, and exact description of the said design. In the accompanying drawing—

Figure 1 represents the front plate.

Figure 2, one of the side plates.

Figure 3, the rear plate; and

Figure 4, the leg of the Eclipse cooking stove.

The front plate A has near each end a plain beading, *a*, and an ornamental scroll, *b*. It has also two doors B B, on which is the oval ornament shown. On the side plate C are three doors, D E and F, having oval ornaments of a character somewhat similar to those on the doors of the front plate. The rear plate H is edged with a plain beading, *f*, and has the three scroll ornaments illustrated, the leg G being ornamented in the manner clearly illustrated in fig. 4.

We claim the design for the plates of a cooking stove, substantially as represented in and by the accompanying drawing.

In testimony whereof we have signed our names to this specification in the presence of two subscribing witnesses.

GARRETTSON SMITH,
HENRY BROWN.
